(57) **CLAIM**

The ornamental design for a ceiling fan light kit globe as shown and described.

DESCRIPTION

FIG. 1 is a top perspective view of a ceiling fan light kit globe showing my new design in the environment of a ceiling fan;

FIG. 2 is a bottom perspective view of FIG. 1.

FIG. 3 is a top view of FIG. 1.

FIG. 4 is a bottom view of FIG. 1.

FIG. 5 is a front side view of FIG. 1.

FIG. 6 is a rear side view of FIG. 1.

FIG. 7 is a right side view of FIG. 1; and,

FIG. 8 is a rear side view of FIG. 1.

Broken lines illustrate environment and form no part of the claimed design.

1 Claim, 8 Drawing Sheets
